(57) CLAIM

The ornamental design for a garment, as shown and described.

DESCRIPTION

FIG. 1 is a front view of a garment showing my design; FIG. 2 is a rear view thereof; FIG. 3 is a first side view thereof; FIG. 4 is a second side view thereof; and, FIG. 5 is a perspective view thereof.

The long-and-short broken lines form an unclaimed boundary around at least a portion of the claimed subject matter, and form no part of the claim. The even-length broken lines, which show the remainder of the article, are directed to environment, represent unclaimed subject matter, and form no part of the claim.

The contrast in shading represents a contrast in appearance only and does not represent any particular color, material, texture or finish. The hatch represents a generic mesh textile.
